(57) **CLAIM**

The ornamental design for a luggage wheel assembly, as shown and described.

DESCRIPTION

FIG. 1 is a back left perspective view of a luggage wheel assembly;

FIG. 2 is a second back left perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The broken lines in the drawings illustrate environmental subject matter that forms no part of the claimed design.
